CONTAINER FILLING AND CLOSING MACHINE

Thomas E. Piazze, Mount Vernon, Ohio, assignor to Continental Can Company, Inc., New York, N.Y., a corporation of New York

Filed Apr. 22, 1959, Ser. No. 808,112

23 Claims. (Cl. 53—266)

This invention relates to packaging machinery and is more particularly concerned with improvements in a machine for receiving a container formed of pliable sheet material from a container forming machine, filling the container with a commodity, closing the top of the filled container and sealing the same.

It is a general object of the invention to provide an improved container filling and closing machine having a pocketed conveyor for receiving open topped tube-like containers which are formed of pliable heat sealable material from a container making machine or other source of supply and for advancing the containers beneath apparatus positioned along the path of the conveyor for filling each container with a predetermined quantity of a product, for tucking the outstanding top portions of the end walls of the filled container while bringing the connecting side wall portions into juxtaposed relation to form a flat closure, for heat sealing the closed top of the filled container, and for delivering the closed packages thus formed from the machine.

It is a more specific object of the invention to provide an improved container filling and closing machine which comprises a continuously operated conveyor having a series of removable pocket forming mandrels for receiving in upright open position flat bottom bags formed of heat sealable film material, the conveyor being arranged to travel in a generally horizontal plane with the bags in upright position thereon and to advance the bags successively beneath a device for filling each bag with merchandise, a top closing mechanism for tucking the end walls of the bag top to form a bellows fold therein and for bringing the side walls of the bag top into flat face-to-face relation, a mechanism for cross sealing, folding and finally sealing the folded bag top, a mechanism for folding over and pressing the sealed portion against the top wall and a mechanism for delivering the filled and closed bags from the machine.

It is another object of the invention to provide in a machine of the type described an improved folding and tucking mechanism for bringing the top portions of successive filled bags into closed relationship by placing in the end walls thereof bellows fold and bringing the side walls into contiguous flat folded relation.

It is a further object of the invention to provide in a machine of the type described improvements in the mechanism for sealing the tops of the filled bags after they have been closed by a folding and tucking mechanism which sealing mechanism forms an initial cross seal in the flat bag top, folds over the sealed portion onto itself and finally cross seals the folded over portion.

It is still another object of the invention to provide in a machine of the type described an improved mechanism for receiving successive pairs of open flat bottom bags from a supply line and for seating the bags in pocket forming mandrels on a continuously operated conveyor for transfer to successive bag filling, closing and sealing mechanisms.

Another object of the invention is to provide in a

2

container forming, filling and closing apparatus a mechanism for transferring containers from an intermittently operating container fabricating machine in multiple side-by-side relation to upwardly opening container receiving mandrels which are arranged in single file relation on a continuously traveling conveyor which carries the same to successive container filling, top closing and sealing apparatus.

It is a still further object of the invention to provide in a container filling and closing machine wherein open topped bags are delivered to pocket forming mandrels on a continuously traveling conveyor which presents the successive bags to a filling mechanism an improved apparatus for vibrating the mandrels as bags therein are being filled in order to settle the material in the bags before the top closing operation.

It is still another object of the invention to provide in a container filling, closing and sealing machine an apparatus for pressing the tops of the filled bags after the closing and sealing operation to provide a package which in its final form is of rectangular cross section.

These and other objects and advantages of the invention will be apparent from a consideration of the container filling and closing machine which is shown by way of illustration in the accompanying drawings wherein:

Figure 1 is a front side elevation with portions broken away and with other portions omitted of a machine which embodies the principal features of the invention;

Figure 2 is a plan view of the machine with portions thereof removed or broken away;

Figure 41 is a view similar to Figure 40 at the later stage of the bag top tucking and closing operation;

Figure 42 is a view similar to Figure 40 at the completion of the tucking and closing operation;

Figure 43 is a perspective view of the bag top as it appears after the first cross sealing operation;

Figure 44 is a perspective of the bag top after the top fold is formed and the final cross seal is applied; and

Figure 45 is a perspective view of the bag top upon completion of the final seal pressing operation.

The machine illustrated in the drawings is adapted to receive a series of bags of the square bottom type which are formed of heat sealable sheet or web material, to fill successive bags with a product, to fold and seal the top of each bag and deliver the completed packages formed thereby from the machine. The illustrated machine is particularly adapted for use in conjunction with a container fabricating machine of the type in which a series of forming mandrels are carried in double line arrangement on an endless conveyor and sheets of relatively

tightly flexible container forming material are folded over the end of the mandrels to form flat bottom containers having vertical side seams, the containers being removed from the mandrels and delivered through a transfer mechanism to the machine in which the present invention is embodied. A suitable machine for fabricating the containers is disclosed in my copending application Serial No. 657,853, filed May 8, 1957. The present machine is an improvement on the machine disclosed in my co-pending application Serial No. 660,299, filed May 20, 1957.

The machine shown in the drawings comprises, briefly, a continuously driven endless conveyor supported on an upright frame structure for movement in a horizontal plane, which conveyor is provided with a series of upwardly opening pocket forming mandrels in which flat bottom containers or bags are adapted to be received from the container fabricating machine. A bag feeding mechanism is arranged at Station A (Figures 1 and 2) along the back or rear run of the conveyor for delivering successive pairs of bags in upwardly open relation into the mandrel pockets in the horizontal conveyor. A suitable filling mechanism (not shown) is arranged at Station B at the end of the machine which is to the right as viewed in Figure 1, which filling mechanism is operative for feeding a measured amount of a product, for example coffee, into the open top of each successive bag. A bag top tucking mechanism is arranged at Station C along the front run of the conveyor for forming bellows folds in the top margins of the end walls of each bag and for bringing the side walls into flat face-to-face relation. A vibrating mechanism is preferably provided between Stations B and C for settling the contents in the bag as it is filled and advanced to the tucking head. The tuck folded and closed top of each bag is double cross sealed and the sealed top is folded upon itself after which a final seal is applied by a combination heat sealing and fold forming mechanism arranged at Station D along the front run of the conveyor. The closed and sealed bag is then advanced by the conveyor to a top pressing mechanism at Station E, at the left end of the machine as viewed in Figure 1, after which the completed package is dropped through the bottom of the mandrel pocket in which it is carried to a discharge conveyor at Station F which delivers it from the machine.

The machine comprises a generally rectangular upright support member or base 10 (Figures 1 to 4) on which the operating mechanisms are supported by means of a frame structure arranged on the top of the base which frame structure comprises laterally spaced upstanding front and rear side frame members 11 and 12. The side frame members 11 and 12 are connected by suitably positioned transversely extending brace members and end structures which will be hereinafter referred to. The various mechanisms which operate on the bags 13 are positioned at Stations A, B, C, D, E and F (Figure 2) and are supported on the side frame members 11 and 12 or on cross frame structures which also serve to connect and brace these side frame members.

A supporting and guiding frame structure 14 is mounted on the upper edges of the side frame members 11 and 12 for the bag carrying conveyor 15, the frame structure 14 extending above the upper edges of the vertically disposed side frame members 11 and 12 and guiding the conveyor 15 for movement in a horizontal plane. The conveyor 15 comprises a pair of vertically spaced endless carrier members 16 and 17 (Figures 34 to 37) which are formed by short sections of chain links 16' and 17' connected in paired vertical alignment by vertically extending mandrel supporting plates 18, the latter spacing the chain sections 16' and 17', and forming combination support and guide members on which bracket supports 20 for the pocket forming mandrels are secured. The conveyor 15 is carried at the filling end

of the machine (Station B) on a sprocket formation 26 (Figure 4) which comprises upper and lower sprocket plates 27 and 27' mounted on a connecting hub 28 which is keyed to a sleeve member 29 secured on the vertically extending drive shaft 30. The vertical shaft 30 is rotatably mounted in an end support frame which comprises upper and lower horizontally disposed plates 32 and 32'. The plates 32 and 32' extend in vertically spaced fixed relation above the side frame members 11 and 12 and are connected between the latter. The vertical shaft 30 is supported in the vertically spaced bearings 31 and 31' and has a driving connection at its lower end (not shown) with the main drive for the machine or with a separate source of power so as to form a drive through the sprocket formation 26 for the conveyor 15. The shaft 30 is adapted to support at its upper end a mechanism (not shown) for opening or spreading the tops of successive bags 13 and for filling each bag with a measured amount of the product being packaged.

The conveyor 15 is supported at the opposite end of the machine (Station E) on an idler sprocket formation 33 (Figures 30 and 31). The sprocket formation 33 comprises vertically spaced upper and lower sprocket plates 34 and 35 which are mounted on a connecting hub 36. The hub 36 is secured to a vertically disposed bearing sleeve 37 which is rotatably mounted on an upstanding post 38. The post 38 has a lower end section of reduced diameter which is secured in a depending boss 39 on the horizontally disposed bottom member 40 of an end frame 41 which connects the ends of the side frame members 11 and 12 and extends above the latter at the end of the machine. The end frame 41 comprises the bottom frame member 40, which extends a substantial distance toward the center of the machine, and which may be in the form of a casing, and an upper or top plate-like frame member 42 to one end of which the top of the post 38 is secured. The top plate member 42 is supported at its inner end by a channel-like bracket member 43 extending upwardly from the bottom frame member 41.

The conveyor 15 is supported and guided along its front and back runs between the end sprockets 26 and 33 in guide rail formations or assemblies 44 and 45 (Figure 2) which constitute the main portions of the frame structure 14. The guide rail assemblies 44 and 45 extend along the front and back sides of the machine and are supported on the upper edges of the vertical side plates 11 and 12. The guide rail assemblies 44 and 45 are identical and only one will be described. The guide assembly 45 (Figures 34 to 38) comprises top and bottom rails 46 and 47 connected by and held in vertically spaced relation by the vertically disposed support plate 48. The upper rail 46 is provided with a downwardly opening guide slot or recess 50 and the bottom rail 47 is provided with an upwardly opening guide recess 51, the two guide recesses or tracks 50 and 51 being in vertical alignment and being adapted to receive the upper and lower ends of the base plates 18 so as to hold the plates 18 in vertical position during travel of the conveyor. The upper rail formation 46 is provided with a top guard plate 52 which has its outer edge extending over the edge of the rail 46 and forming a guard over the top portion of the supports 20 for the bag mandrels.

The plates 18 of the conveyor 15 are guided at the filling end of the machine (Station B) by track forming upper and lower oppositely facing recesses (not shown) provided in the peripheral margins of the horizontal support plates 32 and 32'. At the top pressing end of the machine (Station E) vertically spaced horizontal upper and lower guide plates 53 and 53' are secured by upright posts 54 to the bottom end frame member 41 and have their marginal edges recessed (not shown) to form upper and lower tracks which are aligned with the tracks 50 and

51 so as to guide the conveyor plates 18 around that end of the machine.

The vertical conveyor plates 18 each carry on the inner face thereof a pair of vertically spaced guide rollers 55 and 55' (Figures 34 to 38) which are mounted on support pins 56 and 56' and which are positioned to engage with the opposed horizontal faces of the upper and lower guide rails 46 and 47. Each plate 18 is provided with a centrally disposed, vertically extending, elongate slot 57 forming a guide way or track for a slide member 58 on which a mandrel support 20 is mounted. The slide member 58 has an inner portion 59 which is of reduced width and which extends into the guide slot 57 and carries on its inner face a cam roller 60 mounted on a horizontally extending pin 61. The slide member 58 is of lesser length than the length of the guide slot 57 so that it has a limited vertical movement in the slot 57 relative to the support plate 18. The cam roller 60 normally engages with a longitudinally extending cam rail 62 which holds the support assembly 20 in its uppermost position.

Each of the bag mandrel support assemblies 20 (Figures 34 to 38) comprises a vertically extending back or base plate 63 which has a boss 64 on its outside face with a vertically extending central recess 65 adapted to receive the slide plate 58 so as to center the assembly 20 on the slide plate 58. The back plate 63 is bolted or otherwise attached to the slide plate 58 so that it travels with the latter. The back plate 63 is positioned outside of the guide channels 46 and 47 slightly and its upper edge is adapted to travel beneath the overhanging edge portion of the top guard plate 52 on the top rail 46. The back plate 63 has a pair of integral outwardly extending, vertical wings or side plates 66 and 66' which are in spaced relation in the direction of travel of the conveyor and which extend above a pair of horizontally disposed outwardly extending plate sections 67 and 67', the inner confronting edges of which are provided at the outer ends thereof with aligned elongate pivot slots 68 and 68' for receiving pivot pins 69 and 69' extending from the side edges of a perforated bottom plate 70 so that the latter has a sliding pivot connection or mounting. Tension springs 71 and 71' which are housed in the recesses 72 and 72' provided in the plate sections 67 and 67' are connected at one end to the pivot pins 69 and 69' and anchored at the other end in the recesses 72 and 72' so as to urge the bottom plate 70 inwardly toward the base plate 63 when the bottom plate 70 is in closed horizontal position and hold its inner edge on the ledge forming top edge of the vertical support plate 73 which is secured on the base plate 63. The bottom plate 70 carries a cam roller 74 which is adapted to engage with opening mechanisms which will be hereinafter described. The side plates 66 and 66' are spaced apart a sufficient distance to receive between them a portion of a removable pocket forming bag receiving and supporting mandrel 75 (Figures 35 and 39).

The mandrel 75 (Figure 39) may be conveniently formed by shaping two plate sections as shown and joining them to form an open ended tubular member of rectangular cross section having outwardly flared flanges 76 at the top end and outwardly directed vertical fins 77, 77' extending from the oppositely disposed side walls 78, 78', which form vertical flanges adapted to be bolted or otherwise fastened to the outer edges of the side members 66 and 66' of the assembly 20. The open bottom of the mandrel 75 is seated on the perforated bottom plate 70 when the latter is in closed position. The mandrel 75 may be interchanged with any of the assemblies 20 and different size mandrels 75, as indicated in Figure 35, may be provided for varying the size of the bag which the machine will accommodate. The mandrel 75 may be varied in length and width with the overall dimension in the plane of the fins 77, 77' remaining constant so that the mandrels may be properly seated and held in any of the supporting assemblies 20.

The empty bags 13 are supplied to the pocket forming mandrels 75 in pairs from a suitable source, preferably an intermittently operating duplex bag making machine associated with the present apparatus such as disclosed in my copending application Serial No. 657,853. The bags 13 are delivered to the conveyor 15 at Station A in Figure 2 and fed by a conveyor, or the like, to a delivery mechanism 80 (Figures 3 and 5). The bags 13, in opened up condition, are delivered to a vertical hopper 81 which is mounted on a movement imparting supporting structure 82. The hopper 81 comprises a vertical front plate 83 and a back plate 84 with the back plate 84 having a rearwardly flared upper flange section 85. The hopper 81 is of generally rectangular cross section and open at the top and bottom. It is divided into two separated spaced bag receiving sections or passageways 86 and 86' by vertically extending channel-like members 87 and 87' positioned between the front and back wall plates 83 and 84 and spaced a distance apart corresponding to the spacing of the mandrels 75 on the conveyor 15 as shown in Figure 3.

The hopper 81 is supported by the movement imparting structure 82 in outwardly extending relation relative to the main frame of the machine so that the bottom end is positioned above and in vertical alignment with the open tops of the pocketed mandrels 75 on the conveyor 15. It is supported for movement in a closed four motion path so as to deliver the bags 13 two at a time to the pockets in the mandrels 75 on continuously advancing conveyor 15 beneath the same. The front plate 83 of the hopper 81 is connected by a box-like formation 88 extending from a cross plate 90 on the front plate 83 to the upper end of a vertically extending slide plate 91. The slide plate 91 is supported in a bracket 92 which is in the form of a generally T-shaped casting and which has a vertically extending guideway forming recess 93 within which the plate 91 is mounted for vertical reciprocation. The carriage forming bracket 92 has two side arms 93 and 93' extending in the longitudinal direction of the machine and pivotally attached at 94 and 94' to the upper ends of a pair of generally vertically extending link members 95 and 95'. The links 95 and 95' are secured at their lower ends on pivot shafts 96 and 96' which extend between the side frame plates 11 and 12. The two links 95 and 95' are also pivotally connected intermediate their ends to opposite ends of a longitudinally extending link 97. A lever arm 98 is secured to the pivot shaft 96' and extends downwardly therefrom with a cam roller 99 on its lower end which is adapted to engage with a plate cam 100 (Figures 3 to 6) carried on a cross cam shaft 101 extending between the side frame members 11 and 12. The carriage bracket 92 is connected at its trailing end by a pair of horizontally extending tension springs 102 with a fixed part 103 of the main frame of the machine. The springs 102 are connected at one end to a bracket plate 104 which is carried on the pivot 94 and at the other end to a bracket plate 105 which is secured to a cross bar 103 extending between the supporting frames for the conveyor guide rails. The springs 102 resist the movement of the carriage 92 in the direction of the advance of the conveyor 15 and hold the cam roller 99 in engagement with the cam 100 while permitting reciprocating longitudinal movement of the carriage 92.

The vertical movement of the slide plate 91 is controlled by an angular arm 106. The arm 106 is mounted on the pivot shaft 107 which extends between the side frame members 11 and 12. A cam lever arm 108 is secured on the shaft 107 which carries a cam roller 110 engaging with the plate cam 111 which is mounted on the cam shaft 101 adjacent the cam 100. The lifting lever 106 carries at its free end a roller 112 which engages with a bottom cross plate 113 on the slide plate 91 so that swinging movement of the lever arm 106 raises and lowers the slide plate 91. The carriage bracket 92 carries a small bracket 114 on its inner face on which a

roller 115 is rotatably mounted on a vertical axis in position to engage with the outer face of the cross link 97 on the carriage 92, to hold the slide plate 91 in vertical position.

5 A suction device is associated with the conveyor 15 at Station A to insure proper seating of the bags in the pocket forming mandrels 75 which comprises a suction box 117 having an open top 118 aligned beneath the path of the mandrels 75 so that suction is applied to the bags 13 through the apertures in the bottom of the mandrels 75 as the latter slide over the open top 118 of the suction box. The suction box 117 is connected by a suitable conduit 119 to a motor driven pump (not shown) which may be mounted in any convenient location on the machine frame structure.

10 After the bags are received in the pocket forming mandrels 75 they advance by movement of the conveyor 15 around the filling end of the machine where a predetermined quantity of a commodity is deposited in each of the bags by a rotary filling head mechanism (not shown) at Station B which carries a series of filling nozzles and which is supported on and rotates with the vertical shaft 30. The filling mechanism is of a type which delivers successive measured charges through the nozzles as the 15 mechanism rotates about its supporting shaft, the nozzles being advanced in aligned relation with the bags 13 in the mandrels 75 on the conveyor 15. A suitable filling mechanism is disclosed in copending application Serial No. 663,471, now Patent No. 2,888,046. The filling 20 mechanism is provided with a no-bag no-fill control mechanism (not shown) so that a charge is delivered to a mandrel 75 only when there is a bag 13 in the latter.

25 As the bags are filled by the filling mechanism at Station B, they are preferably vibrated or shaken by a vibrating mechanism 120 (Figures 7 to 11) which extends from Station B toward the bag top closing mechanism at Station C. The vibrating mechanism 120 comprises a channel-shaped vibrator rail 121 (Figure 8) having a straight section 122 (Figure 7) which extends along the front 30 run of the conveyor 15 and a curved end section 123 which extends around a portion of the filling end of the machine. The straight section 122 of the vibrator rail is secured to the front side bar 124 of a rectangular frame 35 125 which is arranged in a generally horizontal plane and has a pair of clamp ears 126 and 126' at the rear corners thereof for securing the frame on a pivot shaft 127. The pivot shaft 127 is journaled in upright supports which comprise the vertical posts 128 and 128' extending between the horizontal end support plates 32 and 32' and connected by heavy brace rods or bars 129. The horizontal plates 32 and 32' are connected at this point by spaced vertical posts 130. The curved end section 123 of the vibrator rail 121 is secured to an end bracket 131 which is fastened to the end of an extended portion of 40 the pivot shaft 127 by the clamp formation 132 so that the entire rail 121 swings upon rotation of the shaft 127, the rail 121 moving in a vertical path of relatively short length and vibrating all of the mandrel support assemblies 20 which have their cam rollers 60 engaged in the track forming recess 133 formed in the rail 121.

45 An operating mechanism is provided for vibrating the rail 121 which is supported on a downwardly extending subframe or bracket structure 135 (Figure 8) which is secured beneath the bottom support plate 32'. The bracket 135 carries a drive shaft 136 journaled at its lower rear edge and having at one end a pulley 137 which is connected by a drive belt 138 with a motor 140 supported on a vertically disposed base forming bracket 141 at the rear side of the machine. The bracket 141 is pivotally connected at 142 to a support bracket 143 extending from the rear frame member 12. Suitable means for 50 adjusting the position of the motor support 141 so as to provide the necessary tension in the drive belt 138 is provided as indicated at 144. The drive shaft 136 is provided at its opposite end with a pinion 145 (Figures 8 55

and 10) which is in driving relation with a gear 146 on an intermediate stub shaft 147 journaled in the bracket 135. The gear 146 is in turn in driving relation with a gear 148 mounted on a cross shaft 150 which is journaled in the forward edge of the bracket 135 and which has a connection at its other end with an upwardly extending pitman or crank rod 151. The crank rod 151 has a bearing forming eye member 152 at its upper end which is rotatably mounted on a pin 153 extending between a pair of spaced bearing ears 154 and 154' depending from the bottom face of the front bar 124 of the frame 125. At its lower end the crank rod 151 is connected to an adjustable eccentric mechanism 155 (Figures 8 to 11). The eccentric mechanism 155 comprises the collar forming member 156 which is secured on the bottom end of the crank rod 151 and is connected by the roller bearing assembly 157 with the hub 158 of an eccentric 160, the latter being rotatably mounted on the shank of a bolt 161 which has a square head 162 slidably mounted in a track forming slot 163 in the outer face of a block member 164 which is secured on the end of the shaft 150. The bolt 161 carries at its outer end a locking clamp nut and washer 165 which permits the bolt 161 to be loosened and moved in the slot 163 to adjust the eccentricity of the connection so as to vary the throw of the crank arm 151. The guide rails for the conveyor plates 18 and the horizontal support bar for the rollers 60 are discontinued at the ends of the vibrator rail 121 and the rollers 60 ride in the guide recess or channel 133 so that the swinging movement or oscillation of the frame 125 imparted by the operating mechanism through crank 151 is transmitted to the bag support assemblies 20 to vibrate or shake the bags carried in the mandrels 75 and settle the contents therein.

As the filled bags are advanced beyond the filling station B, they are moved beneath a tucking head mechanism 170 (Figures 12 to 22) which is mounted on a supporting structure at Station C and which operates to place tucks or bellows folds in the top marginal portions of the end walls of each filled bag 13. The tucking head mechanism 170 operates to place the tucks in the end walls of the filled bag and simultaneously brings the top marginal portions of the side walls into flattened juxtaposed relation so as to close the bag top for subsequent sealing.

The tucking head 170 is mounted on an upright frame or stand structure 171 (Figure 12) projecting in fixed position above a horizontal support plate 172 which is in turn mounted on a pair of cross rails 173 extending between the side frame members 11 and 12. The tucking head 170 is given a four motion movement in an endless path as the tucking and folding operations are accomplished to close the top of the bag while the bag is advancing beneath the same on the conveyor 15. The head structure comprises a vertical slide plate 175 which forms the base for supporting the tucking fingers. A pair of vertically spaced and vertically aligned rod members 176 and 177 extend horizontally and forwardly of the front face of the slide plate 175 and have a vertically disposed bar 178 (Figures 12 to 16) secured to their forward ends. The vertical bar 178 carries a cross bar 180 which extends on opposite sides of the vertical bar 178 adjacent the lower end thereof and which forms a supporting track member for a pair of slidably mounted carriage members 181 and 181', from which tucking fingers 182 and 182' depend in oppositely disposed spaced relation and in alignment in the direction of travel of the bags 13 on the conveyor 15. The tucking finger carriages 181 and 181' are provided with upstanding bracket members 183 and 183' which have their upper ends slotted at 184 and 184' to receive a guide forming cross bar 185, the latter being secured on the vertical bar 178 in parallel spaced relation above the cross bar 180. The finger carriages 181 and 181' are moved on the guide rail 180 by pairs of links 186, 187 and 186', 187'. The 75

links 186 and 187 are pivotally connected to each other and the relative short lower link 87 is connected at 188 to the carriage 181. The longer link 186 extends generally vertically and is connected by the pivot 190 to a cross bar 191 which is secured to the vertical bar 178 in parallel spaced relation above the guide bars 180 and 185. The links 186' and 187' are connected in the same manner to each other and to the carriage 181' and the cross bar 191, respectively. The vertically extending links 186 and 186' are provided intermediate their ends with cam rollers 192 and 192' which are positioned to engage the cam plates 193 and 193'. The cam plates 193 and 193' are secured to the outer ends of pairs of vertically spaced horizontal support pins 194 and 194' which extend from bracket plate members 195 and 195' mounted on opposite sides of a vertically extending track forming support or carriage member 196 for the vertical slide plate 175. The cam plates 193 and 193' are cut out so as to provide lower legs having downwardly and inwardly curved opposite disposed edges forming cam tracks 197 and 197' on which the cam rollers 192 and 192' are adapted to move to bring the tucking fingers 182 and 182' toward each other when the slide plate 175 is lowered. The cam plates 193 and 193' also have upper legs providing on their lower edges cam tracks 198 and 198' which slant upwardly and outwardly in diverging relation from the center of the head and against which the cam rollers 192 and 192' are adapted to engage, when the slide plate 175 is raised, to move the fingers 182 and 182' away from each other.

The vertical bar 178 on the tucking head carries at its lower end a pair of inner tucking members or plates 200 and 200' which are of inverted generally U-shaped so as to provide pairs of depending tucking fingers 201 and 201'. The tucking plates 200 and 200' are mounted on a pair of carriage forming members 202 and 202'. The carriage members 202 and 202' are slidably mounted on a track forming bar or rod 203 which is carried on the lower end of the vertical bar 178 and which extends in the direction crosswise of the machine on opposite sides of the bar 178. The carriages 202 and 202' are provided with upright bracket members 204 and 204' at their inner ends which have their upper ends slotted at 205 and 205' to receive the opposite ends of a guide bar 206 which is carried on the lower end of the vertical bar 178 and which extends parallel with the track forming bar 203. Tension springs 207 and 207' are provided for urging the carriages 202 and 202' towards the outer ends of the guide bar 203 so as to move the tucking plates 200 and 200' apart. The springs 207 and 207' are connected at their ends to the brackets 204 and 204' and looped around upwardly extending portions of the plates 208 and 208' secured on the opposite ends of the track forming bar 203. The tucking plates 200 and 200' are normally held in separated or open relation as shown in Figure 12 and 15 and are adapted to be moved toward each other to the closed position as shown in Figures 14 and 16 during the tucking operation as will be hereinafter described.

The vertically extending slide plate 175 is carried in a guideway or track forming recess 210 provided in the support plate 196. The support plate 196 is formed with a pair of laterally extending wings 211 and 211' (Figure 18) which are connected by pivot bolts 212 and 212' to the upper ends of parallel links 213 and 213'. The links 213 and 213' have their lower ends secured on the pivot pins 214 and 214' which are journaled in pairs of bearing forming ears 215 and 215' at opposite sides of the base of an adjustably mounted bracket or carriage formation 216 which is carried in vertically sliding relation on the upstanding fixed post formation 217 of the head support or stand 171. The carriage bracket 216 encompasses the hollow post 217 and has a top cross bar 216' which is connected in threaded relation with an adjusting screw 218. The cross bar 216' extends through

vertical slots 219 in the front and rear walls of the hollow post 217. The screw 218 is rotatably mounted in the top plate 220 of the post 217 and carries on its upper end a hand wheel 221.

The tucking head 170 is reciprocated in the direction of travel of the conveyor 15 by horizontal movement of the supporting bracket plate 196 which movement is accomplished by cam 222 (Figures 12 and 18) carried on the cross shaft 223 extending between the side frame plates 11 and 12. The cam 222 has a groove in which there is engaged a cam roller 224 carried on the end of the lower arm 225 of bell crank 226 which is pivotally mounted on the cross shaft 227 extending between the side plates 11 and 12. The bell crank 226 has an upstanding arm 228 which is pivotally connected at 230 to a horizontally extending link 231 having its other end secured at 232 to the end of a crank arm 233 mounted on the rearwardly extended end of the pivot pin 214'. The carriage or bracket plate 196 has a small bracket 234 (Figure 12) on the lower end of the rear face thereof which carries a roller 235 mounted on a vertical pin 236 extending in the bracket which roller 235 rides on the front face of the bracket member 216 to hold the carriage plate 196 in vertical position. Vertical reciprocation of the slide plate 175 is controlled by the plate cam 245 on the cross shaft 223. The edge of cam plate 245 is engaged by cam roller 246 on the lower end of the arm 247 of bell crank 248 which is pivotally mounted on the cross shaft 227 and which has an upstanding arm 250 pivotally connected at 251 with a horizontally extending link 252 having its other end pivoted at 253 to the upper end of a crank arm 254 which is secured on the end of the shaft 255, the latter being journaled in extended portions 256 of the bearing brackets 215' on the carriage member 216. At its other end the shaft 255 carries a crank arm 257 which extends in a generally horizontal direction and carries a cam roller 258 which is positioned to engage with a bottom cross piece on the lowermost end of the slide plate 175.

As the conveyor 15 moves a filled bag 13 beneath tucking head mechanism 170, the finger supporting slide plate 175 is lowered until the inside tucking fingers 201 and 201' enter the top of the bag, the head being positioned at the end of its horizontal movement to the right in Figure 13. The outside tucking fingers 182 and 182' are lowered simultaneously on the outside of the end walls of the bag top, the fingers being in the position shown in Figure 13 as they begin the downward movement. As the head is lowered by downward movement of the slide plate 175, the outside tucking fingers 182 and 182' are moved inwardly towards each other to engage the end walls of the bag and to move in between the pairs of inside tucking plates 201 and 201'. As these movements are accomplished, the entire head is moved forward by horizontal movement of the bracket plate 196 with the moving bag. As the bag and head advance the partially tucked bag top moves between a pair of top pressing plates 260, 260' (Figures 13, 20, 21 and 22) which are normally held in a laterally spaced or open position and which are closed on the bag top to bring the side walls together as the advancing movement of the head positions the tucking fingers 182, 182' and 201, 201' between the same.

The top pressing plates 260, 260' (Figures 20 to 22) extend, when closed, in parallel, vertical relation from the ends of a pair of horizontally disposed supporting arm members 261 and 261'. The supporting arm members 261 and 261' are mounted on vertically extending parallel pivot shafts 262 and 262' which are journaled in a horizontally extending portion 263 of a bracket 264 projecting forwardly of the end of a supporting frame or carriage 265 for the sealing mechanism which will be hereinafter described. The pivot shafts 262 and 262' extend at their upper ends above the bracket support 263 and carry a pair of lever arms 266 and 266' which extend toward the pressing plates 260 and 260' and carry at their free ends cam rollers 267 and 267' with the lever arms 266 and 266'

being connected by a tension spring 268 which urges the cam rollers 267 and 267' toward each other and into engagement with a cam plate 270. The cam plate 270 is bolted at 271 to a bracket member 272 extending from a movable frame portion 275 of the sealing mechanism. The cam plate 270 has its trailing end slotted at 276 to accommodate the folded bag top as the bag is advanced toward the seal forming mechanism. A pair of laterally separated, vertically extending, parallel guide plates 277 and 277' are secured by bracket members 278, 278' to the support bracket 263 and a pair of similar parallel spaced guide plates 280 and 280' are mounted on a depending bracket 281 secured to the bracket member 272 on the movable frame 275 of the sealing mechanism for guiding the folded bag top to the sealing mechanism.

The bag top sealing mechanism 290 (Figures 23 to 29) receives the tucked and closed bag top as it is advanced from the tucking head 170 past the pressing plates 260 and 260'. The seal forming mechanism 290 comprises an upright fixed frame or stand 291 (Figures 23 and 28) which is supported on a longitudinally and horizontally extending base plate 292, the latter being mounted between the frame members 11 and 12 on longitudinally spaced cross bars 293. The fixed frame 291 comprises vertically extending side plates 294 and 294', which are spaced in the direction longitudinally of the machine, and connecting top and bottom plates 295 and 295' extending horizontally between the side plates. The two side plates 294 and 294' form vertical rails or tracks members for supporting thereon the vertically adjustable rectangular frame 265 which constitutes the support for the movable sealing and folding elements of the mechanism 290. The vertically adjustable support frame 265 comprises vertically extending end plates 296 and 296' (Figure 24) which have guideway forming recesses 297 and 297' on their opposed inner faces for receiving the vertical track forming end plate members 293 and 293' of the fixed frame 291. The two end plates 296 and 296' are connected at their upper ends by a horizontally extending top plate member 298 which extends lengthwise of the machine between the inner faces of the fixed post 293 and 293'. The top plate 298 carries in depending relation along its front and rear edges parallel rails 300 and 300' (Figures 26 to 28) of L-shaped cross section which form oppositely disposed, vertically extending, parallel tracks 301 and 301' and horizontally disposed, laterally spaced, parallel tracks 302 and 302'. The top plate 298 and the rails 300 and 300' form a guideway for a carriage on which the sealing elements are supported. The end plates 296 and 296' are provided at their top edges with outwardly extending threaded bosses 303 and 303' for receiving the threaded shanks of depending adjusting screws 304 and 304'. The screws 304 and 304' are rotatably mounted in bracket plate members 305 and 305' which extend at opposite ends of the fixed frame 291 and are secured to the top plate 295 thereof. The adjusting screws 304 and 304' carry sprockets 306 and 306' which are connected by a chain 307. One of the screws 304 is provided with a hand wheel 308 for operating both of the screws through the chain 307. The end plates 294 and 294' are also connected along their back edges by longitudinally extending brace bars 310 and 311 (Figure 28).

The bag top sealing and folding elements are carried on a horizontally extending plate 312 which forms a carriage for these elements and which is received in the downwardly opening guide recess in the top portion of the frame 295. The slide plate or carriage forming member 312 is provided along its forward and rearward longitudinal edges with a series of supporting rollers 313 each of which is mounted on a shaft forming 314 extending horizontally from the vertical wall defining one side of a roller receiving recess 315. The rollers 313 may be mounted on suitable ball bearing supports on the pins 314 and are positioned to engage with the track forming portions 302 and 302' of the rails 300 and 300'.

respectively. The plate 312 is also provided along its longitudinal edges with pairs of oppositely disposed rollers 316 (Figures 24 and 26), each pair of which is positioned intermediate adjoining pairs of the rollers 313. Each of the rollers 316 is mounted on a supporting shaft forming pin 317 extending upwardly from a bottom wall defining the lower side of a roller receiving recess 318, with the periphery of each roller extending a sufficient distance beyond the vertical edge of the plate 312 to engage with the vertical track surface 301 or 301'. The rollers 316 serve to guide the plate 312 on a straight line longitudinal movement in the guide housing formed by frame member 298 and associated guide rails 300 and 300'. The rollers 313 support the plate 312 in the guideway forming recess for free sliding, horizontal movement therein.

Movement in the longitudinal direction of the machine is imparted to the plate 312 by a link 320 (Figures 18, 23 and 24) which has one end pivotally connected at 321 to an upstanding ear forming flange 322 on a bracket forming block 323 which is secured on the top surface of the plate and which operates in a slot 324 provided in the plate 312. The link 320 is pivotally connected at its other end to the pivot 212' on the bracket 196 of the bag top tucking mechanism 170 so as to reciprocate the plate 312 horizontally with the bracket 196.

The slide plate 312 forms a support or carriage for forwardly extending seal forming devices 326, 327 and 328 and a folding device 330, the latter being positioned between the second seal forming device 327 and the final sealing device 328. The sealing devices 326 and 327 act successively to form a double seal on the upstanding flat top of each successive bag carried on the conveyor 15. The double sealed bag top is then folded upon itself by the folding device 330 and the folded top is finally sealed with the sealing device 328. The sealing devices 326, 327 and 328 are constructed in an identical manner and all of them are supported in the same manner on the horizontally reciprocated carriage forming plate 312.

The first sealing device 326 (Figures 23 to 26) which performs the initial sealing operation on the folded and flattened bag top comprises a pair of sealing irons 331 and 332 (Figure 26). The outermost sealing iron 332 is bolted or otherwise secured to the outer end of a U-shaped upwardly and inwardly extending bracket 333 having a pair of inwardly curved, longitudinally spaced legs 335 and 335' of generally C-shaped form which extend inwardly to a connecting cross plate 336 which is bolted or otherwise secured to the outer end of a rectangular base plate 337. The base plate 337 is secured on the bottom face of the slide member 312 and is provided on its bottom face with a pair of depending, spaced, parallel track forming rails 338 and 338' which extend transversely of the slide plate 312 and which have oppositely disposed tracks 339 and 339' for receiving a slide plate member 340 which carries at its outer end the sealing iron 331, the latter being bolted or otherwise secured to the end thereof. The slide member 340 is provided at its opposite edges with guideway forming grooves 341 and 341' for receiving the tracks 339 and 339'. At its inner end the slide member 340 is provided with a cam roller 342 which is mounted on a vertically extending support pin 343 depending below the slide member 340. The slide member 340 is also provided at this end with a pair of tension springs 344 having their ends secured to pins 345 on the member 340 and to L-shaped bracket members 346 extending rearwardly of the base plate 337. The springs 344 urge the slide member 340 in a rearward direction to separate the sealing irons 331 and 332 and to hold the cam roller 342 which depends below the slide member 340 in engagement with an operating cam bar 348. The cam 348 is mounted on a bracket 350 which is secured on a longitudinally extending pivot shaft 351, the latter being journaled in the end plates 296 and 296' of the support frame, with the end

plates 294 and 294' of the fixed frame 291 having vertical slots 352 and 352' (Figures 23 and 28) for accommodating the vertical movement of the shaft 351.

The pivot shaft 351 is provided with a lever arm 353 (Figures 23, 24 and 28) which depends therefrom and is connected by the horizontally extending pivot 354 with one end of a link 355, the link 355 having its other end connected by a vertical pivot 356 with the end of a lever arm 357 which has a splined connection with the vertical shaft 358. The shaft 358 is journaled in a bottom bearing bracket 360 which is secured on and extends inwardly of the back side plate 12 of the main frame and a top bearing bracket 361 which is secured on and extends rearwardly of the brace rails 310 and 311 of the vertically adjustable support frame 265 for the sealing and folding devices. The shaft 358 is slidably mounted in the two piece top bearing bracket 361 and the lever arm 357 is confined between the two portions of the bearing bracket 361 so that when the frame 265 is adjusted in the vertical direction the bearing 361 and the arm 357 will slide axially on the shaft 358. The shaft 358 has a stop collar 362 positioned adjacent the bottom bearing bracket 360 which engages with the bearing 360 and holds the shaft 358 in fixed vertical position relative to the main frame member 12. The shaft 358 extends at its lower end below the bearing 360 and carries a lever arm 363 which extends radially of the axis of the shaft in the longitudinal direction of the machine and carries at its free end a cam roller 364 positioned for engagement with a cylindrical cam 365 which is mounted on a cross shaft 366 journaled in the side plates 11 and 12. The cam roller 364 is held in engagement with the track edge on the cam 365 by a tension spring 367 having one end connected to the end of the lever arm 363 and the other end connected by a bracket member 368 to the side frame plate 11. Rotation of the cam 365 swings the longitudinal shaft 351 about its axis and moves the cam plate 348 to open and close the jaw-like heat sealing bars 331 and 332 in timed relation to the movement of the folded bag top and the carriage member 312.

The bag top is guided between the sealing irons 331 and 332 when they are in the open position by the guide members 280 and 280' (Figures 13, 20, 24 and 25) which are mounted on the one arm 335 of the bracket 334 as heretofore described in connection with the bag top tucking mechanism 170.

The second seal forming device 327 is identical with the initial seal forming device 326 and is operated in the same manner to perform a second sealing operation on the folded bag top. The bag top is guided between the first and second sealing devices 326 and 327 by a pair of vertically extending, laterally spaced guide plates 370 and 371 (Figures 24 and 25) which are attached to the bottom ends of a pair of vertically extending, laterally spaced bracket plates 372, the latter being bolted at their upper ends to a bracket member 373 which is secured on an upstanding bracket arm portion 374 of the sealing device 327.

When the second sealing operation is accomplished, the bag is advanced beyond the sealing device 327 to the bag top folding device 330, which folds the uppermost marginal portion of the sealed top of the bag over upon the remaining portion of the bag top with the fold line extending in the longitudinal direction as illustrated in Figure 44. The bag top is held in vertical position and guided to the folding device 330 by a pair of vertically extending, laterally spaced guide plates 375 and 376 which are attached to the bottom ends of a pair of laterally spaced, vertically extending bracket plates 377, the latter being bolted at their upper ends to a bracket member 378 which is secured to the upstanding bracket arm portion 374' of the sealing device 327.

The fold forming device 330 (Figure 27) comprises a bearing forming bracket 380 which is secured on the

extended end of the horizontal support or base plate 381, the latter being secured at its rear end to the bottom surface of the slide plate 312. A small cross shaft 382 is journaled in the bifurcated upper end of the bracket 380 and extends in the longitudinal direction of the machine. A lever arm 383 is secured on the shaft 382 and extends forwardly thereof with a pivot 384 at its outer end on which a depending frame 385 is mounted for swinging movement. A fold plate 386 is secured on the frame 385 and is normally held in the vertical position as shown in Figure 27 with its lower portion parallel with the guide plates 375 and 376. The swinging frame 385 carries a cam roller 387 which is adapted to engage with a plate cam 388 secured on a forwardly extending portion of the bracket 380 and having a vertical track 389 with an upwardly and inwardly extending diagonal top portion 389'. The cam roller 387 is held against the cam track by a tension spring 390 connected at one end to the end of the shaft of the roller 387 and at its other end to a fixed pin 391 on the bracket 380. The shaft 382 carries a gear segment 392 which is in toothed engagement with a gear 393 mounted on a shaft 394 which is journaled in the bracket 380 below the shaft 382. The gear 393 engages with a rack section 395 which is carried on a slide member 396. The slide member 396 has edge grooves and is supported in the track forming members 397 and 397' secured on the bottom of the base plate 381. The slide member 396 carries at its inner end a cam roller 398 which is mounted beneath the slide plate and adapted to engage with a cam bar 400 mounted on the shaft 351 in the same manner as the cam bar 348 for the sealing device 326. A pair of tension springs 401 extend between the pins 402 on the back end of the slide member 396 and an angle bracket 403 extending at the back end of the support plate 381 so that the slide member 396 is normally urged toward the rear of the machine and serves to engage the roller 398 with the cam bar 400. The slide member 396 is first pulled by the springs 401 toward the rear of the machine which raises the fold plate 386 above the fixed guide plate or bar 375 and to the rear of the inner guide plate 376 as indicated in dotted line in Figure 27. When the bag top moves into position in front of fold plate 386 the cam roller 387 moves downwardly on the inclined portion 389' of the cam track and the fold plate moves toward the left as viewed in Figure 27 to fold the top marginal portion of the bag top over the plate 375 and downwardly along the outside face of the latter.

As the bag is advanced by the conveyor 15 beyond the fold forming device 330 toward the final sealing device 328, the folded over portion of the bag top is held folded around the top of the outer guide bar or plate 375 by the fold plate 386. The front guide plate 375 terminates at a point near the end of the fold plate 386 while the back guide plate 376 extends to the sealing device 328 and is attached to the bottom of the back one of a pair of spaced vertical bracket plates 405 which are bolted at their upper ends to a bracket member 406 on the leg portion 407 of the sealing device 328. The front one of the vertical bracket plates 405 supports a relatively short front guide plate section 408 which extends to and is flared outwardly adjacent the end of the front guide plate 375 so as to allow the folded over bag top to move off the guide plate 375 and advance between the guide plates 376 and 408 to the final sealing device 328. The bag top is advanced between the sealing bars of the final sealing device 328 and a final seal is formed in the folded portion thereof. The final sealing device 328 is identical with the first or initial sealing device 326 and operates in the same manner to cross seal the folded over top of the bag after which the bag advances to a top pressing apparatus 415 (Figures 30 and 31) which is supported on the vertically extending end post 38 above the conveyor sprocket formation 33 at the discharge end of the machine.

The top pressing apparatus 415 comprises a horizontally disposed support plate 416 having an upwardly extending hub 417 which is splined to the rotating sleeve 37 on the end post 38. The plate 416 carries in peripherally spaced relation a plurality of bag top pressing devices 420. The peripheral spacing of the pressing devices 420 corresponds to the spacing of the bag carrying mandrels 75 on the conveyor 15 and the support plate 416 is positioned on the rotating sleeve 37 so that the pressing devices 420 are each aligned vertically with a bag carrying or pocket forming mandrel 75 on the conveyor 15.

Each of the bag pressing devices 420 comprises an angular bracket member 421 which is pivotally mounted on a supporting pin 422, the latter being carried in a pair of peripherally spaced bearing ears 423 and 423' on the plate 416. Each angle bracket 421 is arranged with one leg 424 extending radially and in a generally horizontal direction and the other leg 425 extending in a generally vertical direction. The leg 424 has a vertical bore 426 at its outer ends and a smaller vertical bore 427 spaced radially inwardly therefrom. The two bores 426 and 427 are adapted to receive upstanding post members 428 and 429 on a presser plate 430. A split clamping arrangement 431 is provided on the outer end of the arm 424 to clamp the post 429 in position while the post 428 serves as a guide for holding the plate 430 against rotation. The vertical leg 425 of the angle bracket 421 carries on its upper end a cam roller 433 which is positioned to engage the outer edge or cam track forming periphery of a circular cam member 434 which is adjustably mounted on the upper end of the hub 417. The cam arm 425 is provided with an adjustable stop bolt 435 intermediate its ends which is adapted to engage an upper standing stop member 436 on the support plate 416 and a pair of tension springs 437 are connected to the stop member 436 and to the upper end of the arm 425 to constantly urge the presser device 420 toward a position which raises the presser plate 430 to an inoperative position above the top of the bag. The cam member 434 is held in locked relation on the hub 417 by a lock ring 438 and the entire presser assembly is connected for vertical adjustment to the top frame plate 42 to which a reduced portion of the upper end of the post 38 is secured. The top frame plate 42 carries three vertically disposed adjusting screws 442, 443 and 444, which are spaced radially and circumferentially about the post 38 and each of which is threadedly engaged in a threaded bore in the cam member 434. The adjusting screws 442, 443 and 444 have sprockets 445, 446 and 447 at their upper ends which are connected by a chain 448 and one of the adjusting screws 444 has its upper end extended to receive a hand wheel 450 for rotating the same. The height of the apparatus 415 above the conveyor 15 may be adjusted by rotating the wheel 450 to accommodate bags of various heights.

The bag top presser apparatus 415 is adjusted and operated so that as the filled and sealed bag moves around the end of the machine, the presser plate 430 is lowered on the bag top and presses the sealed and folded top against the top of the contents in the bag to fold down the final sealed top portion and to square up the top of the completed package. The bag supporting mandrel carrying assemblies 20 are supported on the sprocket members 34 and 35 and the latter carries a ring guide 451 (Figure 31) on which the rollers 60 ride around the end of the machine. As the bag moves into the back run of the conveyor 15, the presser plate 430 is raised to inoperative position allowing the bag to be advanced by the conveyor 15 to the delivery Station F (Fig. 2), where the completed package is dropped through the bottom of the bag supporting assembly 20 for delivery from the machine in a path extending transversely beneath the conveyor 15.

The bag support assembly 20 has its pivoted bottom plate 70 closed or in horizontal position, as in Figures 34, 35 and 38, when it is carrying a filled and closed bag as it advances to the delivery or discharge Station F and provision is made for swinging the bottom plate 70 to open position in order to discharge the completed package. An upstanding cam plate 451 (Figures 2, 3 and 32) is supported on a bracket plate 452 which extends outwardly of the conveyor guide structure 14 on the outwardly extending bracket arm 453. The cam plate 451 is positioned to engage on the inside of the cam roller 74 which depends from the bottom plate 70 on the support 20 and to force the plate 70 outwardly against the tension of the springs 71 and 71' (Figure 38) so as to release the inner edge of the plate 70 from the latch plate member 73 for downward swinging movement about the pivots 69 and 69'. An upstanding support plate 454 is provided on the bracket plate 452 adjacent the path of travel of the inner edge of the plate 70 to temporarily support the plate 70 when it is moved outwardly by the cam plate 451 until it reaches the discharge opening 455 provided between the bracket 453 and a like bracket 453' which is spaced in advance of the same and connected by an outer longitudinally extending rail 456 on which there is supported an upstanding bumper member 457 against which the plate 70 will strike when it swings downwardly into the opening 455. The support plate 454 is located at the end of an upstanding plate 458 which extends longitudinally at the approach side of the discharge opening 455 and has an inclined upper edge positioned to engage the plate 70 of any empty assembly 20 which reaches this point with the plate 70 pivoted to a depending open position. The open plate 70 is raised to closed position by the plate 458 in order to avoid any interference with the opening mechanism and the top of the discharge chute for the delivery mechanism 460. A similar upstanding plate 459 extends on the other side of the discharge opening 455 beyond the bracket 453' for closing the bottom plates 70 of each assembly 20 as it is advanced by the conveyor 15 beyond the discharge Station F to the bag receiving Station A.

The discharge or delivery apparatus 460 (Figures 32 and 33) comprises a chute formation consisting of a downwardly and forwardly curved back or bottom plate 461 and laterally spaced vertically extending side plates 462 and 462' which are arranged relative to the bottom plate 461 to form a chute with the upwardly opening entrance thereto in a horizontal plane beneath the path of the mandrel supports 20 at the Station F and constituting the discharge opening 455. The upper end of the chute is supported on the brackets 453 and 453'. The chute curves downwardly and forwardly with the bottom plate 461 terminating at the upper run of a transversely extending chain conveyor 465. The chain conveyor 465 is supported on laterally spaced, vertically disposed side frame members 466 and 466' which extend through apertures in the main side frame members 11 and 12 of the machine and which are secured to the frame members 11 and 12 by suitable pairs of vertically extending bracket members indicated at 467, 467' and 468, 468', the side frame members 466 and 466' extending forwardly of the front of the machine a substantial distance.

The conveyor 465 comprises laterally spaced side chains 470 and 470' which are carried on pairs of end sprockets 471, 471' and 472, 472'. End sprockets 471 and 471' are carried on a cross shaft 473 extending at the discharge end of the frame and journaled in the side frame members 466 and 466'. The other end sprockets 472 and 472' are rotatably mounted on a cross bar 474 which extends between the side frame members 466 and 466' and is mounted in elongate bearing slots 475 in the side frame members 466 and 466' with position adjusting mechanisms 476 and 476' mounted on opposite frame members 466 and 466' and engaging with the extended

65
70

75

ends of the cross bar 474 so as to enable the bar 474 to be adjusted lengthwise of the conveyor for providing the proper tension in the chains 470 and 470'. The chains carry at spaced intervals thereon connecting cross bars 477 which are mounted on suitable end brackets 478 and extend between the chains. A bottom plate 480 for supporting the packages while they are advanced by the cross bars or pushers 477 extends between the side frame members 466 and 466' and curves over the discharge end of the conveyor.

Vertically disposed side guide plates 481 and 481' are mounted to extend from the lower ends of the side plates 462 and 462' of the chute with their outer ends curved downwardly over the end of the conveyor. The side plates 481 and 481' are mounted on angle brackets 482 which are connected to the side frame members 466 and 466'. The filled bags are discharged into the chute and slide down the bottom plate 461 to the upper run of the conveyor. They are advanced on the support plate 480 by the pusher bars 477 for delivery over the curved end portion of the bottom plate 480 to a horizontal discharge chute 483 which comprises a bottom support member 484 mounted at one end on a cross bar 485 attached to the base frame portion 10 of the frame structure and side plates 486, 486', the bottom chute member 484 being supported at its outer end on a stand or other supporting structure (not shown) and the side plates 486, 486' being supported on suitable brackets attached to the bottom member 484. The filled bags drop onto the bottom 30 484 of the chute in an upright position and each successive bag is moved forwardly in the chute 483 by a plunger or pusher 490 mounted on the end of a transversely extending rod 491 which is pivotally connected to an operating mechanism at the rear of the machine. The pusher rod 491 is pivotally connected at 492 to one end of a short link 493 which has its other end pivoted at 494 to the lower end of a lever arm 495. The lever arm 495 is connected at its upper end to the shaft 496 which extends between the two upwardly directed bracket members 497 and 497'. An operating arm 498 extends downwardly 35 40 of the shaft 496 and is slotted at 500 to accommodate a cam roller 501 mounted on an arm 502 secured on a stub shaft 503 which extends inwardly of the one bracket 497. The stub shaft 503 carries a gear 504 which is in toothed engagement with a gear 505 carried on the end 45 50 of the drive shaft 506, the latter extending longitudinally of the back side of the machine with one end journaled in the bracket 497 and the other end journaled in the bearing bracket 507 (Figure 6). The drive shaft 506 carries a sprocket 508 which is connected by a chain 510 with a sprocket 511 on the cross shaft 473 and drives the conveyor 470.

The drive shaft 506 (Figure 6) is provided with a sprocket 512 which may be connected to the drive for the bag fabricating machine or any other source of power to provide the primary drive for the machine. At its other end the drive shaft 506 is provided with a bevel gear 512 which engages with the bevel gear 513 on the extended end of a cross drive shaft 514 which is journaled in the main side frame members 11 and 12. The shaft 514 carries a pinion 515 which drives a gear 516 on the cam shaft 223 for operating the bag top tucking mechanism 170, the latter shaft being immediately above the shaft 514. The shaft 223 has a pinion 517 which engages with an idler gear 518 on a cross shaft 520 and the gear 518 in turn engages with a gear 521 on the cam shaft 101 for operating the bag feeding or transfer mechanism 80. The shaft 101 has a sprocket 522 which is connected by a drive chain 523 with a sprocket 524 on the cam shaft 366 for operating the sealing devices on the sealing mechanism 290.

An alternative drive is provided which comprises a motor (not shown) at the filling end of the machine having its output shaft connected by a drive chain or belt 525 with a sprocket or pulley 526 on a stub shaft 527. The

stub shaft carries a gear 528 which engages with a gear 530 on the forwardly extended end of the main shaft 514.

A vertically extending guard plate 531 may be provided around the entire machine which is spaced outside of the path of the mandrel support assemblies 20 and extends a short distance below the same. The guard plate 531 may be supported on the main frame of the machine by suitable brackets.

In operating the machine, pairs of bags 13 in open or set-up condition are delivered to the hopper 81 of the bag feeding mechanism 80 while the hopper 81 is in its uppermost position. The operating mechanism 82 carries the hopper 81 downwardly and forwardly immediately above the mandrels 75 on the conveyor 15 in alignment with a pair of the mandrels 75 to allow the bags to settle into the pocket forming mandrels with suction being applied through the suction box 117 to properly seat the bags in the mandrels. The conveyor 15 travels continuously and advances the bags to the filling station B where a predetermined amount of a product is placed in each of the bags. As the bags are filled and moved past the filling head at the Station B, the bag supporting assemblies 20 are vibrated by operation of the vibrating mechanism 120. The filled bags are advanced from the filling Station B to the tucking mechanism 170 at Station C. The tucking head is moved in a four motion path by its operating mechanism to insert the two pairs of fingers 201 and 201' while they are spaced apart in the top of the bag and to bring the tucking fingers 182 and 182' downwardly and then inwardly against the end walls of the bag through the position shown in Figure 41 to the position shown in Figures 14 and 42. The tucking head moves forwardly with the conveyor and the tucking fingers are brought between the closure plates 260 and 260' which are then operated to move the pairs of tucking fingers 201 and 201' toward each other and into the position shown in Figure 42. The tucking head is then withdrawn from the bag top to repeat the cycle of tucking and closing operations on the next bag. The tucked and flattened bag top advances between the guide plates 277 and 280 to the sealing mechanism 290. The movable frame 265 of the sliding mechanism, which carries the sealing devices, is reciprocated in a horizontal path and during its advancing movement travels with the conveyor 15. During each cycle of operation the sealing devices 326 and 327 are operated to place a cross seal in the folded bag top and the folding mechanism 330 is operated to fold over the sealed top for final sealing by the sealing mechanism 328. Each successive bag passes in step-by-step relation through the sealing mechanism 290 and is advanced by the conveyor 15 to the top pressing device 415 at the end of the machine. The sealed bag top is folded down on the top of the bag contents and flattened by a pressure plate 420 as it is carried around the end of the machine by the conveyor 15. The pressure plate 430 is lifted as the bag moves into the back stretch of the conveyor and the filled, closed and sealed bag which comprises a completed package is advanced to the discharge opening 455 (Figure 2) where the bottom plate 70 of the bag supporting assembly 20 is pulled open and the completed package is dropped through the open bottom of the assembly into the downwardly directed chute which leads to the discharge conveyor apparatus 460. The completed package is delivered to the conveyor 470 on its side and moves over the end of the conveyor so that it is deposited on end in the packing chute 486 where it is moved forward in upright relation and into row formation by the reciprocating pusher 490.

While specific materials and particular details of construction have been referred to in describing the form of the machine illustrated, it will be understood that other materials and equivalent structures may be resorted to within the spirit of the invention.

I claim:

1. A bag filling and closing machine having an upright supporting frame structure, a chain conveyor mounted on end sprockets which are supported on longitudinally spaced vertically extending axes arranged at opposite ends of said frame structure, a series of bag supporting assemblies mounted in spaced relation on said conveyor, said assemblies each comprising a supporting bracket having an upright portion attached to the conveyor and a horizontal portion extending outwardly thereof, said horizontal portion having laterally spaced side arm members which define the sides of an opening extending inwardly to said upright portion and a bag supporting plate member mounted in said opening, said supporting plate member having laterally extending, axially aligned pivot pins at the outer ends of the side edges, said side arm members having elongate slots for receiving said pivot pins in sliding pivotal relation therein, tension springs connected to said side arm members and said pivot pins and normally urging said supporting plate member toward said upright portion, a ledge formation on said upright portion positioned to support the inner edge of said supporting plate member when it is in horizontal position, a cam member on the bottom face of said supporting plate member adjacent the outer edge thereof and means on said frame structure for forcing said cam member outwardly to release said supporting plate member for downward and outward swinging movement about said pivot pins whereby to allow a bag supported thereon to drop vertically through said opening for discharge from the conveyor.

2. A bag filling and closing machine having an upright supporting frame structure, a chain conveyor mounted on end sprockets which are supported on longitudinally spaced vertically extending axes arranged at opposite ends of said frame structure, a series of bag supporting assemblies mounted in spaced relation on said conveyor, said assemblies each comprising a supporting bracket having an upright portion attached to the conveyor and a horizontal portion extending outwardly thereof, said horizontal portion having an opening extending from the outer side thereof toward said upright portion, a bag bottom supporting plate in said opening, said supporting plate having a pivotal and slidable connection with said horizontal bracket portion adjacent the outer edge thereof, means on said upright bracket portion for supporting the inner edge of said supporting plate in horizontal position and means on said frame structure for engaging said supporting plate and for sliding said supporting plate outwardly on its pivotal connection to release the same for downward swinging movement whereby to permit discharge through said opening of a bag supported on said assembly.

3. A bag filling and closing machine having an upright supporting frame structure, a chain conveyor mounted on end sprockets which are supported on longitudinally spaced, vertically extending axes arranged at opposite ends of said frame structure, a series of bag supporting assemblies mounted in spaced relation on said conveyor, said assemblies each comprising a supporting bracket having an upright portion attached to the conveyor and a horizontal portion extending outwardly thereof, said horizontal portion having an aperture forming a bottom opening, a bag bottom supporting plate pivotally and slidably mounted in said opening, means normally holding said supporting plate in horizontal position in said opening and means on said frame structure for sliding said supporting plate on its mounting so as to release the same from said holding means for downward pivoting whereby to permit a bag which is supported thereon to be discharged through said bottom opening.

4. A bag filling and closing machine having an upright supporting frame structure, a chain conveyor mounted on end sprockets which are supported on longitudinally spaced, vertically extending axes arranged at opposite ends

of said frame structure, a series of bag supporting assemblies mounted in spaced relation on said conveyor, said assemblies each comprising a supporting bracket having an upright portion attached to the conveyor and a horizontal portion extending outwardly thereof, said horizontal portion having spaced, outwardly extending arm members which define the side edges of an outwardly opening bottom aperture, said arm members having confronting inside faces with opposed elongate bearing recesses therein, a plate-like member in said bottom aperture having axially aligned pivot formations extending into said bearing recesses, tension springs connected to said pivot formations and said arm members for urging said plate-like member in the direction of the inside edge of said bottom aperture, a latch element which is effective to hold said plate-like member against pivoting movement when said plate-like member is at its innermost position, a cam member on said plate-like member and a cooperating cam member on said supporting frame for sliding said plate-like member outwardly against the force of said springs so as to disable said latch element and permit said plate-like member to swing downwardly to a bottom opening position.

5. A bag filling and closing machine having an upright supporting frame structure, a conveyor mounted for generally horizontal movement on said frame structure, said conveyor comprising vertically spaced chains carried on pairs of spaced end sprockets which are supported on longitudinally spaced, vertically extending axes arranged at opposite ends of said frame structure, a series of bag supporting assemblies mounted in outwardly extending spaced relation on said conveyor, said assemblies each comprising an angle bracket having an upright portion and a horizontal portion extending outwardly thereof, said horizontal portion having means thereon providing a pocket for supporting a bag therein, said upright portion having a vertically extending rectangular plate attached to the inner face thereof and a supporting and guiding frame formation extending along said conveyor between said pairs of end sprockets, which supporting and guiding frame formation comprises vertically spaced guide rails having oppositely disposed, longitudinal guide recesses on the opposed faces thereof in which the top and bottom ends of said rectangular plate are seated.

6. A bag filling and closing machine having an upright supporting frame structure, a chain conveyor mounted on end sprockets which are supported on spaced vertical axes on said frame structure, a series of bag holding assemblies mounted in spaced relation on said conveyor, said holding assemblies each comprising an angular supporting bracket having an upright portion attached to the conveyor and a horizontal portion extending outwardly thereof, said horizontal portion having a pivotally and slidably mounted bottom forming section adapted to swing downwardly when unsupported to provide an opening in the horizontal portion for discharge of a bag therethrough, pocket forming means for supporting a bag on each holding assembly in vertical alignment with said discharge opening, means on each said assembly for normally supporting said bottom forming section at one edge thereof and cam means positioned along said conveyor for engaging said bottom forming section and for sliding the same off of its supporting means so as to permit said bottom forming section to swing downwardly.

7. In a bag filling and closing machine having an upright supporting frame structure, a conveyor comprising vertically spaced chains mounted on pairs of vertically spaced end sprockets which are rotated on longitudinally spaced, vertically extending axes arranged at opposite ends of said frame structure, a series of bag supporting assemblies mounted in spaced relation on said conveyor, said assemblies each comprising a supporting bracket having an upright portion attached to the conveyor and a horizontal portion extending outwardly thereof for receiving an upright pocket forming member, said upright

portion having a vertically extending rectangular plate, guide rollers on the inner face of said plate, a guide structure for said rectangular plate which extends at predetermined points along said conveyor, said guide structure having vertically spaced track formations for cooperation with said guide rollers, and a vibrator device positioned along said conveyor which vibrator device comprises an elongate guide rail having an outwardly opening track formation for receiving one of the guide rollers on the rectangular plate of each successive assembly, said guide structure being interrupted adjacent the ends of said guide rail, a horizontally disposed vibrator frame extending inwardly from said elongate guide rail and secured thereto, and means for swinging said vibrator frame to impart a vertically reciprocating motion to said elongate guide rail.

8. In a bag filling and closing machine having an upright supporting frame structure, a conveyor comprising vertically spaced chains mounted on pairs of vertically spaced end sprockets which are rotated on longitudinally spaced, vertically extending axes arranged at opposite ends of said frame structure, a series of bag supporting assemblies mounted in spaced relation on said conveyor, said assemblies each comprising a supporting bracket having an upright portion attached to the conveyor and a horizontal portion extending outwardly thereof for receiving an upright pocket forming member, said upright portion having a vertically extending rectangular plate, guide rollers on the inner face of said plate, a guide structure for said rectangular plate which extends at predetermined points along said conveyor, said guide structure having vertically spaced track formations for cooperation with said guide rollers, and a vibrator device positioned along said conveyor which vibrator device comprises an elongate guide rail having a track formation for engaging with one of the guide rollers on the rectangular plate of each successive assembly, a swingably mounted vibrator frame secured to said vibrator rail and means for swinging said vibrator frame to impart a reciprocating movement to said guide rail.

9. In a bag filling and closing machine, an upright supporting structure, a conveyor mounted on said supporting structure for advancing movement in a horizontal plane, said conveyor having a series of pocket forming members mounted in spaced relation thereon for supporting bags in upright position, a cam roller on each of said pocket forming members, a vibrator mechanism comprising a vibrator frame swingably mounted at one end on said supporting structure, a guide rail on the free end of said vibrator frame which is positioned to engage with the cam rollers on said pocket forming members along a portion of their path of travel, and means for reciprocating said vibrator frame to vibrate said pocket forming members in a direction transversely of the path of advancing movement of said conveyor.

10. In a bag filling and closing machine as recited in claim 9, and means for varying the movement of said vibrator frame without interrupting the operation of the machine.

11. A bag closing machine having a continuously traveling horizontal conveyor for supporting filled bags in spaced upright position, a bag top tucking mechanism comprising a fixed stand positioned at a predetermined point along said conveyor, and a bag top tucking head mounted for vertical adjustment on said stand, said tucking head comprising a vertical slide plate, a vertical bracket spaced forwardly of said slide plate and having track forming members extending horizontally in directions longitudinally and transversely of the path of advance of said conveyor, pairs of carriages mounted on said tracks, a pair of outer tucking fingers mounted on the carriages on the longitudinally extending tracks, pairs of inner folding fingers mounted on the carriages on the transversely extending tracks, said vertical slide plate being mounted for vertical movement on a carriage plate, said carriage

plate being mounted on spaced pairs of swinging arms for horizontal movement on said stand, means to move said slide plate and said carriage plate in timed relation to the movement of the conveyor to position said tucking and folding fingers vertically for engagement with the top marginal portions of each successive bag and to advance the same horizontally with each bag during a predetermined portion of its movement, and means to move the carriages on each of the tracks toward each other so as to move the tucking and folding fingers relative to each other to infold end wall portions of the bag top and to bring the opposed side wall portions thereof into flat folded relation.

12. In a bag closing machine having a continuously moving conveyor for supporting thereon in upright spaced relation a series of filled bags, a bag top tucking station, a fixed stand at said station and a bag top tucking device mounted for vertical adjustment on said stand, said tucking device comprising a pair of outer tucking fingers slidably mounted on a track forming bracket for movement toward and from each other in a vertical plane, two pairs of inner fold forming fingers for cooperation with the outer tucking fingers, said pairs of inner fingers being slidably mounted on a track forming bracket which extends transversely of the path of movement of said conveyor, said track forming brackets being mounted on a vertical slide plate, said vertical slide plate being slidably mounted on a horizontal carriage, said carriage being mounted for horizontal movement on parallel arms which are pivoted on said stand, means to move said slide plate vertically and said carriage horizontally in timed relation to the movement of the conveyor to insert said fold forming fingers into the top of each successive bag and to advance the same with each bag during a predetermined portion of its movement, means responsive to movements of said slide plate to move the tucking fingers toward each other to infold end wall portions of the bag top between said pairs of fold forming fingers and means to move said pairs of fold forming fingers toward each other upon infolding movement of said tucking fingers thereby to bring the opposed side wall portions of the bag top into flat folded relation.

13. A bag closing machine having a continuously traveling conveyor and means thereon for supporting a series of filled bags in upright position, a fixed stand mounted at a tucking station along said conveyor and having a vertically adjustable frame member, a bag top tucking device on said stand, said tucking device comprising a pair of outer tucking fingers slidably mounted on a track forming member extending in the direction of advance of said conveyor, two pairs of inner folding fingers adapted to cooperate with the outer tucking fingers, said inner folding fingers being slidably mounted on a track forming member extending transversely of said conveyor, said track forming members being mounted on a bracket which is attached to a vertical slide plate, said vertical slide plate being mounted on a carriage which is pivoted on the upper ends of spaced pairs of vertically extending arm members, said arm members being pivoted at their lower ends to said vertically adjustable frame member on said stand, means to move said slide plate vertically and means to swing said arm members to move said carriage horizontally in timed relation to the movement of the conveyor so as to position said tucking fingers and said folding fingers for engagement with the top marginal portions of the walls of each successive bag and to advance the same with each bag during a predetermined portion of its movement, means operative upon downward vertical movement of said slide plate to slide the tucking fingers toward each other and means to slide the pairs of folding fingers toward each other whereby to infold the top portions of the end walls and to bring the opposed side wall top portions into flat folded relation.

14. In a bag closing machine wherein the filled bags are supported in upright position on a continuously traveling

conveyor, a bag top tucking device mounted for vertical adjustment on a fixed stand, said device comprising a pair of outer tucking fingers mounted on spaced carriages which are slidable on a track extending in the direction of travel of the conveyor, two pairs of inner folding fingers mounted on spaced carriages which are slidable on a track extending transversely of the direction of travel of the conveyor, said tracks being attached in forwardly spaced relation to a vertical slide plate, said vertical slide plate being slidably mounted on a vertically disposed carriage, said carriage being mounted for horizontal movement on a pair of parallel links extending upwardly from said stand, means to reciprocate said slide plate and said carriage in timed relation to the movement of the conveyor to lower said folding fingers into the open top of each successive bag and to advance the same with each bag during a predetermined portion of its movement, means to slide the tucking finger carriages toward each other when the slide plate is moved downwardly, a pair of swinging plate members mounted on opposite sides of the conveyor and means to operate said plate members to engage with the top margins of the bag side walls and force said folding fingers toward each other as the tucking fingers are moved toward each other whereby to infold end wall portions of the bag top and bring the opposed side wall portions thereof into flat folded relation.

15. In a bag closing and sealing machine having a continuously traveling endless horizontal conveyor on which the bags are carried in spaced relation in an upright position and means for flat folding the tops of filled bags, mechanism for cross sealing the flattened tops of the filled bags comprising a vertically adjustable frame extending along said conveyor, a plate-like carriage mounted for horizontal reciprocating movement on said frame, two heat sealing and pressing devices mounted in spaced relation on said carriage and a fold forming device mounted on said carriage between said sealing and pressing devices, each of said sealing and pressing devices having cooperating sealing bar members which are mounted for movement relative to each other for clamping engagement with the tops of bags carried on the conveyor beneath said devices, one of said sealing bars being fixed on a bracket extending laterally of said carriage, the other sealing bar being mounted on a bracket which is slidably transversely of said carriage, a cam roller on said slidable bracket, a cooperating cam bar mounted on a cam shaft, means for horizontally reciprocating said carriage in timed relation to the movement of the conveyor so that said carriage advances with the conveyor for a predetermined portion of the travel of the conveyor and at the same speed, and means for simultaneously oscillating said cam shaft to move said sealing bars into bag top sealing relation while the carriage is advancing with the conveyor and thereafter to move said sealing bars out of engagement with the bag tops for return movement of said carriage.

16. In a bag filling and closing machine having an endless traveling conveyor mounted for movement in a horizontal plane, a series of upwardly opening pocket forming members on the conveyor for supporting bags therein, means for operating said conveyor continuously, a series of successive work stations along said conveyor, mechanism at the first station for delivering empty bags in opened up condition into the pocket forming members, mechanism at successive stations along said conveyor for filling the bags with a product, for closing, cross sealing, folding and finally sealing the top portions of the bag walls, and a top pressing mechanism comprising a movable support, a series of pivotally mounted presser plates on said support and means for moving said support and said presser plates relative to said conveyor to engage the top of each successive bag with a presser plate and to hold the presser plate in engagement therewith while the bag traverses a predetermined portion of its path.

17. A bag filling and closing machine having an upright supporting frame structure, a continuously traveling end-

less conveyor mounted on end supports arranged at opposite ends of said frame structure and supported on longitudinally spaced, vertically extending axes, a series of bag supporting assemblies mounted in spaced relation on said conveyor, said assemblies each having an upwardly opening pocket in which a bag is adapted to be seated in upright position, a series of devices mounted along said conveyor for delivering bags to the pockets in said assemblies, for filling the bags with a product, for closing, cross sealing, folding and finally sealing the top marginal portions of the bags, and a bag top pressing mechanism mounted above the end of said conveyor, which top pressing mechanism comprises a horizontally disposed turret plate mounted above a conveyor end support for rotation on the same axis as the conveyor end support and in timed relation thereto, a series of bracket members swingably mounted in spaced relation on the periphery of said turret plate, each of said bracket members having a vertically extending portion and an outwardly extending portion, a presser plate member on the outwardly extending portion, means normally holding said presser plate member in an elevated position, and means engaging the vertically extending portion for swinging said bracket to move said presser plate member into pressure applying engagement with the closed and sealed top of a bag carried in a pocket forming member on said conveyor as said pocket forming member is advanced by said conveyor around the end thereof.

18. A bag filling and closing machine having an upright supporting frame structure, a continuously traveling endless conveyor mounted on end support members which are rotatably supported on longitudinally spaced, vertically extending axes arranged at opposite ends of said frame structure, a series of bag supporting assemblies mounted in spaced relation on said conveyor, said assemblies each having an upwardly opening pocket forming member in which a bag is adapted to be seated in upright position, a series of mechanisms mounted along said conveyor for delivering bags to said pocket forming members, for filling the bags with a product, for closing, cross sealing, folding and finally sealing the mouth forming portions of the bags, and a bag top pressing mechanism mounted above the end of said conveyor, which top pressing mechanism comprises a horizontally disposed turret frame member mounted for rotation on the same axis as the conveyor end support, a series of bracket members pivotally mounted in spaced relation on the periphery of said turret frame member with each of said bracket members having an arm extending vertically and another arm extending radially outwardly of the axis of said turret frame member, a presser plate on the outwardly extending arm, resilient means normally holding said presser plate in an inclined elevated position, and a cam engaging the vertically extending arm for pivoting the bracket to swing the presser plate into pressure applying engagement with the closed and sealed top of a bag carried in a pocket forming member on said conveyor as said pocket forming member is advanced by said conveyor around the end thereof.

19. A bag filling and closing machine having an upright supporting frame structure, a continuously traveling endless chain conveyor mounted on end sprockets which are supported at opposite ends of said frame structure on longitudinally spaced, vertically extending axes, a series of bag supporting assemblies mounted in spaced relation on said conveyor, said assemblies each having an upwardly opening pocket forming member in which a bag is adapted to be seated in upright position, a series of mechanisms mounted along said conveyor for delivering bags to said pocket forming members for filling the bags with a product, for closing, cross sealing, folding and finally sealing the top marginal portions of the bags, and a bag top pressing mechanism mounted above the leading end of said conveyor, which top pressing mechanism comprises a horizontally disposed turret plate

mounted for rotation on the same axis as the conveyor end sprocket, a series of angle bracket members pivotally mounted in spaced relation on the periphery of said turret plate, each of said angle bracket members having one arm extending in a vertical direction and the other arm extending radially outwardly of the axis of said turret plate, a presser plate member on the outwardly extending arm, spring means normally holding said presser plate member in an elevated position, and a cam engaging the vertically extending arm for moving said arm outwardly to swing said presser plate member into pressure applying engagement with the closed and sealed top of a bag carried in a pocket forming member on said conveyor as said pocket forming member is advanced by said conveyor around the end thereof.

20. A bag filling and closing machine having an upright supporting frame structure, a continuously traveling endless chain conveyor mounted on end sprockets which are supported on longitudinally spaced, vertically extending posts arranged at opposite ends of said frame structure, a series of bag receiving pocket forming members in spaced relation on said conveyor, a series of mechanisms mounted along said conveyor for delivering bags to said pockets, for filling the bags with a product, for closing, cross sealing, folding and finally sealing the top marginal wall portions of the bags, and a bag top pressing mechanism, which top pressing mechanism comprises a turret mounted for rotation about the same post as the conveyor end support, a series of bracket members pivotally mounted in spaced relation on the periphery of said turret with each of said bracket members having vertically and radially outwardly extending portions, a presser plate member on the outwardly extending portion, means on said turret for normally holding said presser plate member in an elevated position, and means for moving said bracket to swing said presser plate member into pressure applying engagement with the closed and sealed top of a bag carried in a conveyor pocket, as the same is advanced in a path beneath said turret.

40 21. A bag filling and closing machine having an upright supporting frame structure, a continuously traveling endless conveyor mounted on end supports arranged at opposite ends of the frame structure on longitudinally spaced, vertically extending axes, a series of bag supporting assemblies mounted in spaced relation on said conveyor, said assemblies each having an upwardly opening pocket in which a bag is adapted to be seated in upright position, a series of devices mounted along said conveyor for delivering bags to said pocket forming members, for filling the bags with a product, for closing, cross sealing, folding and finally sealing the top marginal portions of the bags, and a bag top pressing mechanism mounted above the leading end of said conveyor, which top pressing mechanism comprises a turret mounted for rotation on the same axis as the conveyor end sprocket, a series of bracket members swingably mounted in spaced relation on the periphery of said turret, each of said bracket members having a radially extending portion, a presser plate member on the radially extending portion, means on said turret for swinging said bracket members to move said presser plate into and out of pressure applying engagement with the closed and sealed top of a bag carried in a pocket on said conveyor as said pocket is advanced by said conveyor around the end thereof, and means for adjusting the height of said turret while the conveyor and turret are traveling.

22. In a bag filling and closing machine having an endless traveling conveyor mounted for movement in a horizontal plane, a series of upwardly opening pockets on the conveyor for supporting bags therein, said pockets each having pivoted bottom members for discharging bags therethrough, a series of successive work stations along said conveyor, a mechanism at the first station for delivering empty bags in opened up condition into the 75 pocket forming members, mechanism at successive sta-

tions along said conveyor for filling the bags with a product, for closing, cross sealing, folding and finally sealing the top portions of the bag walls, a bag discharge mechanism comprising a transversely extending conveyor mounted beneath the bag supporting conveyor at a bag discharge station intermediate the ends of said bag supporting conveyor and mechanism for releasing the pivoted bottom members of successive pockets on the conveyor at the bag discharge station so as to deposit the bags on the transversely extending conveyor, said transversely extending conveyor having a horizontal package chute at the delivery end thereof and a reciprocating pusher member for pushing the filled and sealed bags into line forming relation.

23. In a bag filling and closing machine having an endless traveling conveyor mounted for movement in a horizontal plane, a series of upwardly opening pockets on the conveyor for supporting bags therein, said pockets each having pivoted bottom members for discharging bags therethrough, a series of successive work stations along said conveyor, mechanism at the first station for delivering empty bags in opened up condition into the pocket forming members, mechanism at successive stations along said conveyor for filling the bags with a prod-

5
10

uct, for closing, cross sealing, folding and finally sealing the top portions of the bag walls, a bag discharge mechanism comprising a downwardly and forwardly curved discharge chute having an open upper end at a discharge station intermediate the ends of said bag supporting conveyor and beneath the same, mechanism for releasing the pivoted bottom members of successive pockets on the conveyor at the bag discharge station so as to deliver the filled and sealed bags to the discharge chute, a transversely extending conveyor at the bottom of said chute for receiving the bags from the discharge chute on their side faces, said transversely extending conveyor having its delivery end arranged above a horizontal package chute, said package chute receiving the bags on end and a reciprocating pusher member for pushing the filled and sealed bags into line forming relation.
